UNITED STATES PATENT OFFICE.

BERNARD M. CARNEY, OF MCKEESPORT, PENNSYLVANIA.

DESIGN FOR A FLUSH-TANK.

SPECIFICATION forming part of Design No. 26,409, dated December 15, 1896.

Application filed November 10, 1896. Serial No. 611,675. Term of patent 14 years.

To all whom it may concern:

Be it known that I, BERNARD M. CARNEY, a citizen of the United States, residing at McKeesport, in the county of Allegheny and State of Pennsylvania, have invented and produced a certain new and original Design 5 for Flush-Tanks for Water-Closets; and I do declare the following to be a full, clear, and exact description of the invention, such as will enable others skilled in the art to which it appertains to make and use the same.

My invention has relation to a design for a flush-tank for water-closets.

It relates to the entire construction and configuration of the tank, and especially to a tank constructed of one piece of vitreous material, such as porcelain, earthenware, or hard rubber.

My invention relates particularly to a flush-tank for water-closets, as illustrated in the accompanying drawings, in which—

Figure 1 is a front elevation of a tank embodying my design. Fig. 2 is a top plan view, and Fig. 3 is a longitudinal section.

1 represents the rectangular tank, the upper front edge and sides of which are formed with a horizontal flange 2, extending around the three mentioned sides.

3 is a vertical circular orifice extending

through the bottom 4, and on the outside 30 thereof is a circular boss or flange 5.

6 represents a circular sleeve projecting vertically from the bottom 4, and its periphery is formed with a series of semicircular circumferential grooves 7.

On the inside of the tank appears an inverted-U-shaped siphon 8, one leg, 9, of which is connected to the bottom, and the other leg, 10, terminates a short distance above the bottom, as shown in Fig. 3.

12 represents a concave valve-seat, and a series of orifices 13 appear in the shorter leg of the siphon.

All of the corners are rounded, as shown, and the size may be increased or diminished 45 to suit the requirements to which the tank may be put.

Having thus fully described my invention, what I claim as new, and desire to secure by Letters Patent of the United States, is—

The design for a flush-tank for water-closets, substantially as herein shown and described.

In testimony whereof I hereunto affix my signature in presence of two witnesses.

BERNARD M. CARNEY.
